UNITED STATES PATENT OFFICE

GLENN E. McFADDEN, OF DETROIT, MICHIGAN, ASSIGNOR TO LINCOLN MANUFACTURING COMPANY, OF DETROIT, MICHIGAN, A CORPORATION OF MICHIGAN

DESIGN FOR A BRACKET BACK FOR A SIDE-WALL LIGHTING FIXTURE

Application filed November 5, 1930. Serial No. 37,544. Term of patent 7 years.

To all whom it may concern:

Be it known that I, GLENN E. McFADDEN, a citizen of the United States, residing at Detroit, county of Wayne, State of Michigan, have invented a new, original, and ornamental Design for a Bracket Back for a Side-Wall Lighting Fixture, of which the following is a specification, reference being had to the accompanying drawing, forming part thereof.

Fig. 1 is a front elevation of my lighting fixture.

Fig. 2 is a side elevation of my lighting fixture.

I claim:

The ornamental design for a bracket back for a side wall lighting fixture as shown.

GLENN E. McFADDEN.
